UNITED STATES PATENT OFFICE.

WILLIAM T. SMITH, OF BELLEFONTAINE, OHIO, ASSIGNOR OF ONE-HALF TO GEORGE W. SMITH, OF BELLEFONTAINE, OHIO.

TUBULAR DOOR-LOCK.

1,072,668.

Specification of Letters Patent.

Patented Sept. 9, 1913.

Application filed September 5, 1912. Serial No. 718,692.

To all whom it may concern:

Be it known that I, WILLIAM T. SMITH, a citizen of the United States, residing at Bellefontaine, in the county of Logan, State of Ohio, have invented certain new and useful Improvements in Tubular Door-Locks, of which the following is a specification.

This invention relates to door locks, for inner as well as for front doors, and one object of the invention resides in the peculiar shape and construction of the tumbler which makes the lock very safe and almost impossible to pick.

Another object of the invention is to provide a lock of very simple construction and easy to assemble and put in place in the door; little other work being required than boring holes, while another object is to make the lock reversible, that is any lock can be used left or right handed by merely reversing the bars.

In the drawings one embodiment of the invention has been shown in the different figures and Figure 1 represents a vertical section of the lock inserted in a door, with some parts in elevation. Fig. 2 is a section on line 2—2 of Fig. 1; Fig. 3 is a side elevation seen from the inside of the door, showing the bar lock arrangement; Fig. 4 is a section on the line 4—4 of Fig. 3; Fig. 5 is a section on the line 5—5 of Fig. 3; Fig. 6 is a top plan view of the bolt; Fig. 7 a similar view to Fig. 6 with the tumbler shown in place; Fig. 8 is a side elevation of the knob bar partly in section and with the bearing sleeve for the bar; Fig. 9 is a top plan view of Fig. 8 partly in section; Fig. 10 is a vertical section of the door on the line 10—10 of Fig. 1; Fig. 11 is a front view of the lock in position in the door and Fig. 12 is a detail view of the tumbler.

In the drawings, A is the dead bolt, which is preferably made from a cylindrical steel bar, with a vertical slot 20 in the middle thereof. On the upper side of the bolt are cut two narrow notches 21 and 22 which are intended to engage with corresponding lugs 23 on the tumbler B. On the under side of the bolt is provided another notch 24 for engagement with the key and a recess 25 at the rear end serves as a guide-way for the tumbler spring 55 and as a seat for its holding block 54.

The housing C of the lock comprises two tubular inward extensions 26 and 27, the

tube 26 being intended for the dead bolt, and the tube 27 for the latch bolt. The tube 26 is provided with an opening 28 on top for the tumbler, and screw holes 29 at its rear end for rigidly securing the tumbler in the tube. On its under side it has a downward vane or key plate 30 which extends across a longitudinal opening 32 for the tumbler in the bottom of the tube 26. One or more wards 30^b are provided on each side of the key hole 30^a in the key plate. Above the tube 26 the other tube 27 is situated and likewise extending inward from the face plate 33 of the housing. This latter tube 27 of the housing C is intended as a bearing for the latch bolt D, and provided with a wide cut 34 on one side. In this cut 34 the roll back 35 operates, as will be described further. The tube 27 is closed at its rear end by a bottom plate 36 which serves as an abutment for a compression spring 37, which with its other end impinges the rear of the latch bolt D, always pushing it outward, so that the beveled point 38 of the bar protrudes beyond the face plate. The latch bolt D is retained in the housing by a screw 39 adapted to run in a slot 40, in the tube 27. The latch bolt D is provided with a recess 41 on each side, and the rear side of these recesses are rounded to form suitable bearing surfaces for the knob finger 35, or else a stud 42 may be placed on each side for the same purpose. The object of having two of these recesses 41, although there is only one knob finger or roll back 35, is for the purpose of making the latch bolt reversible, so that the lock can be right or left handed as required, by merely turning the latch bolt around 180° on its axis. For this purpose a screw hole on each side of the latch bolt has also been provided for the screw 39.

The usual square section spindle 43 for the knobs or handles 44 is situated beneath the latch bolt D and near its middle, the roll back 35 is mounted around this knob spindle 43. The roll back 35 has an adjusting screw 45, by means of which the finger of the roll back can be adjusted sidewise on the spindle. The upward projecting part of this roll back operates in the slot 34 of the tube 27 and impinges with the stud 42 or the rounded rear face of the recess 41 on one side of the latch bolt D.

The inside locking device for the latch bolt consists of a disk 46 keyed on the knob 110

spindle 43. This disk has a deep notch 47 on one side, and coöperating with this notch is a tooth 48 on a lever 49 situated adjacent the disk on the inside of the door. A small handle 50 for adjusting the lever in its two positions in, or out of engagement with the disk is provided at the end of the lever, and an inclined flange 51 near the handle is intended to be actuated by a key 52 inserted from the outside of the door into the key hole 53. As will be readily understood the knob handles will then be prevented from turning and from revolving the roll back 35, so that unless the key 52 first unlocks the lever 49 the door cannot be opened from the outside. This feature of the invention is particularly intended for use in guest rooms in hotels.

As already described the tumbler B is secured in the lower tube 26 by means of screws 29 which are threaded in the holding-block 54 which fits in the recess 25 of the dead bolt A with sufficient clearance on all sides. The holding block has a transverse slit into which is inserted a spring 55, and the screws 29 also serve to retain said spring in the holding block. At the free end of the spring 55 is secured an inverted T-piece, with its T projections 56 in the axial direction of the bolt. At the upper end of the T-piece are provided two transverse studs 23 which are adapted to engage with one pair or the other of the notches 21, 22 in the bolt A, whereby the bolt will be retained by said studs 23 in either one of its two positions.

Supposing now that a door, provided with this lock, has been shut and locked with the dead bolt A, and that also the inside locking device is in action, the following operations will be required to open the door: The key for the bolt is first inserted into the key hole 38 and turned in the usual manner, when it will first raise the tumbler B when impinging with the lower face thereof. The dead bolt A will thereby be released from engagement with the studs 23 of the tumbler so that by a continued turning of the key, the dead bolt will be withdrawn when the key enters the notch 24. While still continuing to turn the key, it will permit the tumbler to be lowered by its spring 55 when the studs 23 will enter the other pair of the notches 21 in the dead bolt A, thereby securely holding it in its withdrawn position. The key 52 is now inserted in the key hole 53 and turned until the lever 49 disengages the disk 46, whereupon the handle will be free to turn the roll back 35 and draw back the latch bolt D. It will be evident that, by simply swinging the lever 49 into engagement with the disk 46 on the knob-spindle, the lock is converted into a self closing spring lock, working independent of the knob-spindle 43;

and by disengaging the lever, the knob-spindle may be turned freely from either side.

I claim:

1. A tubular door lock having a housing 70 with a tubular extension, a key-plate suspended from said tubular extension, a plurality of wards in said key plate.

2. A tubular door lock having a cylindrical locking member; a housing comprising 75 a face plate and tubular inward extension thereon, forming a bearing for said member and having a central key plate suspended from said extension; and a plurality of wards in said key plate.

3. A tubular door lock having a housing with tubular extensions, one of said tubular extensions being provided with a central longitudinal slot on its under side, a key plate suspended from said tubular extension 80 bridging said longitudinal slot.

4. A tubular door lock having a housing with tubular extensions, one of said tubular extensions being provided with a central longitudinal slot on its under side, a key 90 plate suspended from said tubular extension bridging said longitudinal slot, and a plurality of wards in said key plate.

5. A tubular door-lock having a housing, a tubular extension in said housing, a key 95 plate suspended from said tubular extension, a cylindrical dead bolt mounted to slide in said tubular extension, a central longitudinal slot in said bolt and a tumbler operating with one end in said slot and with its other end rigidly secured in said 100 housing, said tumbler being constructed to hold the bolt in different positions and normally impinging with said key plate.

6. A tubular door lock having a housing, 105 a tubular extension in said housing, a cylindrical dead bolt mounted to slide in said tubular extension, a central longitudinal slot in said bolt and a tumbler constructed to hold the bolt in different positions; said tumbler comprising a holding block securely fastened in said housing a spring extending from said holding block and an inverted T-piece at the free end of the spring operating in said central slot, its horizontal arms extending in the longitudinal direction of said plate, said T-piece having transverse projections and a plurality of notches in said plate for engaging with said projections whereby the bolt is rigidly held 115 in a plurality of different positions by said tumbler.

7. A tubular door-lock having a housing, a tubular extension in said housing, a key plate suspended from said housing, a cylindrical dead bolt mounted to slide in said tubular extension, a central longitudinal slot in said bolt and a tumbler at one end 125 securely fastened in said tubular extension and constructed to hold the bolt in differ- 130

ent positions; a shoe-piece on said tumbler operating in said central slot; said shoe-piece normally contacting with said key plate and being adapted to impinge with the key so as to raise the tumbler from said key plate upon turning the key whereby the tumbler will be disengaged from said bolt.

The foregoing specification signed at Washington, D. C., this fourth day of September, 1912.

WILLIAM T. SMITH.
